UNITED STATES PATENT OFFICE.

HENRI DE BOISCHEVALIER, OF DETROIT, MICHIGAN, ASSIGNOR TO SOCIETE DU CARBURATEUR ZENITH, OF LYON, FRANCE, A CORPORATION OF FRANCE.

VENTURI AND METHOD OF MAKING THE SAME.

Application filed October 20, 1922. Serial No. 595,878.

To all whom it may concern:

Be it known that I, HENRI DE BOISCHEVALIER, a citizen of the United States, residing at Detroit, in the county of Wayne and State of Michigan, have invented a new and useful Improvement in Venturis and Methods of Making the Same, of which the following is a full, clear, and exact description.

The present invention relates broadly to 10 Venturi tubes, and more particularly to tubes of this character adapted to be used as air chokes for carburetors, and to the method of making the same.

At the present time, it is customary to 15 form air chokes for this general purpose from solid castings, thereby adding unnecessary weight to the carburetor as well as increased cost due to this weight and the machining operations required, or from sheet 20 metal having no outer casing. Construction of the latter type do not provide a sufficient bearing surface within the air passage of the carburetor with which they are used, thereby making it extremely difficult 25 to maintain the same in proper operative position.

This invention provides a venturi comprising an outer casing, preferably of sheet metal so constructed as to permit expansion 30 and contraction thereof as may be required by reason of variations in the carburetor with which it is used, thereby eliminating the necessity of accurately machining the air passage through the carburetor proper, and having an inner member, preferably also of sheet metal, and shaped to form a converging, diverging flow passage therethrough.

In the accompanying drawings, there is 40 shown for purposes of illustration only, one embodiment of the present invention, it being understood that the drawings do not define the limits of this invention as changes may be made in the construction and operation disclosed herein without departing from the spirit or scope of my broader claims.

In the drawings:

Figure 1 is a vertical sectional view 50 through the outer casing of the venturi;

Figure 2 is a similar view through the inner member before it is bent to final shape;

Figure 3 is a vertical sectional view through a complete venturi, and

Figure 4 is a transverse sectional view on the line IV—IV of Figure 3. 55

It will be apparent that where venturis are formed as separate castings, it is necessary not only to machine the exterior surface of the venturi per se, but also the inner surface which forms the air passage through the carburetor. These operations do not increase the efficiency of the carburetor, but are required solely by reason of the construction involved. By this invention the machining of the air passage through the carburetor is made unnecessary as the venturi provided readily accommodates itself to such variations and irregularities as may be occasioned by the casting operation. 65

In accordance with this invention, a venturi may be constructed by separately forming an outer member and an inner member and then assembling the same. The outer member may conveniently be formed of sheet metal to provide a casing 2, the meeting edges 3 of which are left free to permit a slight expansion and contraction of the casing. The inner member 4 may be formed in any desired manner, as by a series of drawing operations, to provide a converging, diverging flow passage therethrough. The upper end of the inner member is preferably bent outwardly to form a flange 5 which is substantially equal to the normal exterior diameter of the casing 2, while the lower 75 end of the venturi is so formed that it may be slipped through the casing 2 and then bent outwardly as illustrated in Figure 3. If desired, it will be clearly understood that the inner member may be bent to the form 80 shown in Figure 3 and the outer casing 2 may be then bent in position therearound. 85

When the parts are in assembled position the end portions of the inner member, by reason of their overlapping engagement 90 with the ends of the outer casing, prevent longitudinal relative movement between the parts. The casing 2 may be formed with an opening 6 adapted to cooperate with a set screw extending through the carburetor wall 100 as is customary in the art. 105

By leaving the meeting edges of the outer casing free, it is possible to utilize the venturi construction with carburetors presenting slight variations in the dimensions of the air passages therethrough. At the same

time, the substantially uniform outer surface of the casing 2 provides a large area of contact with the carburetor whereby the parts are easily held in the desired operative position.

Further advantages of the present invention arise from the simplicity and ease of construction of a venturi of this character whereby the cost of a carburetor may be correspondingly decreased.

I claim:

1. A venturi, comprising an outer casing adapted to be bodily inserted within the air passage of a carburetor, and an inextensible inner sheet metal venturi member carried thereby and extending substantially coextensive therewith, substantially as described.

2. A venturi, comprising an outer casing adapted to be bodily inserted within the air passage of a carburetor, and an inextensible sheet metal venturi member carried thereby, said venturi member having its upper and lower edges extending outwardly over the ends of the casing, substantially as described.

3. A venturi, comprising an outer expandable and contractile casing adapted to be inserted within the air passage of a carburetor, and an inner venturi forming member carried thereby, substantially as described.

4. In a venturi for carburetors, an outer sheet metal casing and an inner member substantially coextensive therewith extending over the ends thereof and carried thereby and shaped to provide a converging, diverging flow passage therethrough, substantially as described.

5. A venturi, comprising an outer expandable and contractile casing adapted to be inserted within the air passage of a carburetor, and an inner sheet metal venturi forming member carried thereby and extending substantially co-extensive therewith, substantially as described.

6. A venturi, comprising an outer expandable and contractile casing adapted to be inserted within the air passage of a carburetor, and an inner sheet metal venturi forming member carried thereby and extending substantially coextensive therewith, said venturi forming member having its upper and lower ends turned outwardly over said casing, substantially as described.

7. A venturi comprising an outer casing of substantially uniform diameter throughout its length adapted to be bodily inserted within the air passage of a carburetor, and an inner inextensible sheet metal venturi member extending substantially coextensive therewith and secured over the ends thereof, substantially as described.

8. As an article of manufacture, a venturi comprising an inextensible sheet metal venturi-shaped member having outwardly flanged upper and lower ends, and an enclosing casing surrounding said venturi member substantially entirely between said ends, said casing and venturi member being adapted to be bodily inserted within the air passage of a carburetor, substantially as described.

9. A venturi comprising a deformable outer casing adapted to be bodily inserted within the air passage of a carburetor, and an inextensible venturi member carried thereby, substantially as described.

10. A venturi comprising an outer sheet metal casing, adapted to be bodily inserted within the air passage of a carburetor, said casing having a substantially constant outer diameter, and an inextensible inner sheet metal venturi member carried by said casing and held in position therein by having its ends turned outwardly over the ends of the casing, substantially as described.

In testimony whereof I have hereunto set my hand.

HENRI DE BOISCHEVALIER.
